J. KELLER.
RIBBON MECHANISM.
APPLICATION FILED OCT. 24, 1913.

Patented June 30, 1914.

UNITED STATES PATENT OFFICE.

JULIUS KELLER, OF FOND DU LAC, WISCONSIN, ASSIGNOR TO HARRIS TYPEWRITER MANUFACTURING COMPANY, OF FOND DU LAC, WISCONSIN, A CORPORATION OF WISCONSIN.

RIBBON MECHANISM.

1,101,633.

Specification of Letters Patent. Patented June 30, 1914.

Application filed October 24, 1913. Serial No. 797,032.

To all whom it may concern:

Be it known that I, JULIUS KELLER, a citizen of the United States, residing at Fond du Lac, in the county of Fond du Lac and State of Wisconsin, have invented certain new and useful Improvements in Ribbon Mechanism, of which the following is a specification.

It is common to drive the ribbon spools of typewriting machines from the spring-actuated drum by which the carriage is advanced. In such an arrangement whenever the feed of the ribbon is stopped, the driving drum will be held against rotation in the direction to drive the parts, and therefore the carriage will not be advanced.

This invention contemplates novel means for automatically effecting a temporary disconnection between the ribbon spools and their driving means whenever the feed of the ribbon is stopped for any cause while the machine is in use, so that the travel of the carriage will not be interrupted.

I have herein shown the invention as embodied in a typewriter in which the reversal of the ribbon feed is effected by means actuated by the operator. In such a machine if the operator fails to notice that the ribbon is all unwound from one spool, the winding means, and therefore the carriage, will come to a stop. By being stopped in this way, considerable strain is placed upon the parts, which is objectionable. Furthermore, the parts sometimes bind, or stick, so that it is difficult to actuate the reversing means, thus causing annoyance to the operator.

In the mechanism herein disclosed, whenever the winding is interrupted, whether from the ribbon being entirely unwound from a spool, or from any other cause, the arrangement is such that a pair of ribbon driving gears will be forced out of mesh, so as to disconnect the ribbon spools from the spring-actuated driving drum and thus permit the carriage to advance freely.

In the accompanying drawings, Figure 1 is a fragmentary elevational view from the right-hand side of a typewriter illustrating a ribbon mechanism embodying the features of my invention. Fig. 2 is a front view of the mechanism. Fig. 3 is an enlarged detailed view of certain parts seen in Fig. 2, but showing said parts in a different position. Fig. 4 is a plan view of a portion of the mechanism.

I will herein describe in detail a mechanism which constitutes the preferred embodiment of my invention, without thereby intending to limit the invention to the exact arrangement or combination described.

60

The novel features of the mechanism will be pointed out in the claims.

The spring-actuated drum which furnishes power for driving the carriage and the ribbon spools is indicated by the numeral 1, 2 being the tape or cord attached to and passing around said drum at one end and connected to the carriage at its other end. A gear wheel 3 is fixed with relation to the drum 1 and meshes with a pinion 4 which is loosely mounted on a shaft 5. A disk 6 is fixed with relation to the pinion 4 and carries a pawl 7 which engages with a toothed wheel 8 rigid on the shaft 5. By means of these parts the shaft 5 is rotated 70 to drive the ribbon spools when the drum 1 is rotated in one direction. A retaining pawl 9 mounted on a suitable stationary bracket 10 engages with the toothed wheel 8 and prevents rotation of the shaft 5 in the opposite direction. On the forward end of the shaft 5 is fixed a worm 10 which meshes with a worm-wheel 11 mounted on a shaft 12 which extends across the typewriting machine. Said shaft is mounted for longitudinal sliding 85 movement in suitable bearings in the upper ends of stationary frame pieces 13 and 23. A cap piece 14 is secured by screws 15 to the upper end of the frame piece 13 and overlies the shaft 12 in its bearing. The cap piece 90 has lugs 16 which lie in a groove 17 in the hub of the worm wheel 11, and further has lugs 18 which engage the hub 19 of a spiral gear wheel 20, which is loosely rotatable on the shaft 12. The lugs 16 and 18 prevent 95 axial movement of the worm wheel 11 and the spiral gear 20. The connection between the shaft 12 and the worm wheel 11 is such that the shaft may slide through said worm wheel, but is non-rotatable with respect to 100 said wheel. On the opposite end of the shaft 12 is rotatably mounted another spiral gear 21 which is held from axial movement by lugs 22, engaging the hub of said wheel, said lugs being mounted upon the upper 105 end of the frame piece 23, in which the shaft 12 has a bearing.

The spiral gears 20 and 21 mesh with spiral gears 24, which are fixed upon a pair of vertical shafts 25. On the upper ends of 110

these shafts are mounted the ribbon spools 25^a. A pair of pinions 26 is fixed upon the shaft 12 at the inner side of the spiral gears 20 and 21, said pinions being arranged to alternately engage with pawls 27 carried by the gears 20 and 21, for the purpose of driving the ribbon spools in opposite directions. The shaft 12 may be longitudinally shifted to carry one of the pinions 26 into position to be engaged by a pawl 27 by means of a suitable handle 28 having arms embracing the shaft 12 and lying at opposite sides of a pair of collars 29 fixed on said shaft. The shaft 12 may be held in either one of its operative positions by suitable means herein shown as consisting of a lever 30 pivoted at 30^a in a support 31, and held by a spring 32 in either one of two positions, the spring causing the lever to snap over center.

The forward end of the shaft 5 is rotatably mounted in a bearing member 33, said member being tiltably mounted on a pivot 34 carried by a lug 35 on the frame member 13. The bearing member 33 is offset to form a shoulder 33^a having inclined faces to engage alternately with the end of the lug 35 and thus limit the movement of the bearing member. The bearing 5^a for the rear end of the shaft 5 is sufficiently loose to permit a slight lateral downward movement of the shaft with its bearing 33. A plunger 36 is slidably mounted in a cylinder 37 carried at the outer end of a bracket 38 attached to the frame member 13. A coiled spring 39 presses the plunger 36 upwardly and tends to hold the shaft 5 in its upper position in which the worm 10 meshes with the worm-wheel 11. The tension of the spring 38 is such that under ordinary conditions the worms 10 and 11 will remain in mesh, but if the ribbon feed should be interrupted for any reason, tension will be placed upon the ribbon, the worm wheel 11 will finally cease rotating, and the continued rotation of the driving shaft 5 will force the worm 10 downwardly against the action of the spring 38, and temporarily out of mesh with the worm wheel 11. Thus even though the ribbon spools are at a standstill, the shaft 5 will be permitted to rotate so that the drum 1 may continue to actuate the carriage in the regular way. This action of the driving worm 10 prevents any undue strain upon the parts of the mechanism, and also prevents the parts from sticking or binding, so that no difficulty is presented in shifting the shaft 12 to reverse the ribbon feed.

60 I claim as my invention:

1. In a typewriting machine, the combination with the ribbon spools of driving means therefor including a pair of intermeshing gears, and means for holding said gears in mesh and permitting the gears to

slip out of mesh when undue strain is placed upon the parts.

2. In a typewriting machine, the combination with the ribbon spools, of driving means therefor including a pair of gears, a movable bearing for one of said gears, and a spring tending to hold said gears in mesh, and permitting the gears to slip out of mesh when undue strain is placed upon the parts.

3. In a typewriting machine, the combination with the ribbon spools, of driving means including a worm-wheel, a rotary shaft arranged to have a lateral movement, a worm fixed on said shaft, and adapted to mesh with said worm-wheel, and spring means tending to hold said shaft in the position with said worms in mesh, and arranged to permit the worms to slip out of mesh when undue strain is placed on the parts.

4. In a typewriting machine, the combination with a pair of vertical ribbon spool shafts, spools thereon, a spring-actuated carriage-advancing drum, a rotary shaft extending from front to back of the machine and operatively connected at its rear end to said drum, a shaft extending transversely of the machine and operatively connected to said ribbon spool shaft, intermeshing gears on said transverse shaft and said front-and-back shaft, and spring means tending to hold said gears in mesh and permitting slippage of the gears when the feed of the ribbon is interrupted.

5. In a typewriting machine, in combination, a spring-actuated carriage-advancing drum, a shaft extending from front to rear of the machine and operatively connected to said drum at its rear end, a movable bearing for the forward end of said shaft, a pair of ribbon spools, a gear operatively connected to the ribbon spools for driving them, a gear fixed on the forward end of the first mentioned shaft and meshing with the first mentioned gear, and spring means tending to hold the bearing in position with said gears in mesh.

6. In a typewriting machine, the combination with the supporting framework and the spring-actuated carriage-advancing drum mounted therein, of a rotary shaft extending from front to rear at one side of the machine, and operatively connected at its rear end to said drum, the rear end of said shaft having a bearing in the framework which permits lateral swinging movement of the forward end of the shaft, a bearing pivoted in the framework and supporting the forward end of said shaft, a gear fixed on the forward end of said shaft, a second gear meshing with the first gear, a pair of ribbon spools operatively connected to the second gear, and a spring-pressed plunger acting on said pivoted bearing, and tending to hold said shaft in the position

in which said gears are in mesh, said plunger being arranged to yield to permit said gears to slip out of mesh when undue tension is placed upon the ribbon spools.

- 5 7. In a typewriting machine, the combination with the ribbon spools, of means for driving the spools, comprising a rotary shaft mounted to have a lateral movement, a gear fixed on said shaft, a second gear meshing therewith and operatively connected with the ribbon spools for driving the latter, a

movably mounted bearing in which said shaft is mounted, and a spring tending to maintain said bearing in the position in which said gears are in mesh.

15

In testimony whereof I hereto affix my signature in presence of two witnesses.

JULIUS KELLER.
